CLAIM

The ornamental design for the end standard for picnic table, as shown and described.

DESCRIPTION

FIG. 1 is a top plan view of the end standard for picnic table showing our new design;

FIG. 2 is a side elevational view;

FIG. 3 is a bottom plan view; and

FIG. 4 is a front elevational view thereof.

The picnic table depicted in broken lines is for illustrative purposes only and forms no part of the claimed design.
